UNITED STATES PATENT OFFICE.

JACOB E. DAVIS, OF IRONTON, OHIO.

GAS HEATING-STOVE.

1,258,992.

Specification of Letters Patent. Patented Mar. 12, 1918.

Application filed January 26, 1916. Serial No. 74,372.

To all whom it may concern:

Be it known that I, JACOB E. DAVIS, a citizen of the United States, residing at Ironton, in the county of Lawrence and 5 State of Ohio, have invented certain new and useful Improvements in Gas Heating-Stoves, of which the following is a specification.

This invention relates to gas heating 10 stoves and particularly to that general class of such stoves having an open front and an incandescent heat-producing element.

The primary object of the invention is to produce a heating stove as above outlined, 15 in which the flame is broken up and retarded which causes it to incur a secondary mixture with the air and produce a perfect combustion and hotter flame, as well as a combustion that is free from carbon and the 20 conditions that form poison gas, such as carbon monoxide, to which ends, one feature of the invention resides in providing a fire-resisting clay back for open front gas stoves embodying in its construction a roughened 25 surface so fashioned as to retard the flame and induce it to cling to the fire back throughout the entire surface thereof. A further object of the invention is to so construct the clay fire back that it may be 30 quickly heated, and to so position it with respect to the stove structure as to deflect the heat downwardly and outwardly in intense rays that quickly displace the cold air. To this end, another feature of the invention 35 consists in incorporating a fire back, such as proposed as the essence of the present invention, in a gas heating stove such as disclosed in U. S. Letters Patent No. 964,405, issued July 12, 1910, to the present 40 inventor.

Further characteristics and features of the invention will be hereinafter described in the detailed description of the accompanying drawing, and particularly pointed 45 out in the subjoined claims.

In said drawing—

Figure 1 is a front elevation of a stove illustrating the application of the invention;

Fig. 2 is a sectional view on the line 2—2, Fig. 1, and

Fig. 3 is an enlarged detail view of the fire back.

Referring to the drawings in detail, the 55 invention will be described as especially applicable to a stove embodying such char-

acteristics as are disclosed in the Letters Patent above referred to. 1 represents the stove body which is preferably constructed of sheet metal and has an open front 2. 60 Disposed toward the top is a deflecting or radiating plate 3, which is inclined downwardly and rearwardly, and from its lower edge, the back plate 4 extends downwardly, which according to the present invention 65 embodies a fire back produced from a conventional grade of fire-resisting clay of any desired color, having a roughened or serrated surface formed by the outwardly projecting and staggeredly arranged knobs or 70 fingers 5, some of which, preferably those closest to the flame, are of a solid triangularly formed body having the apex of one angle disposed toward the direction of the flame, while the uppermost knobs or fingers 75 are preferably formed V-shape with their sharpest points disposed toward the flame and their sides flaring toward the uppermost edge of the back plate. The back plate 4 terminates adjacent a series of suitable 80 burners 6. Extending downwardly from the direction of the lower edge of the back plate 4 is the deflecting plate 7 which terminates at one end in the front opening 2 of the stove and at its rearward end in an 85 integral and forwardly disposed portion 8, which forms a head or support for the burners 6 and is provided with a series of openings 8' whose purpose is to permit a current of air to pass in front of the burners 6. 90 The series of burners 6, which are preferably of the Bunsen type, are secured in parallel relation upon a plate 9, which is in turn secured to the side walls of the stove casing by the flange 10 and through its connection 11 with the castings 12. 13 represents the fuel delivery conduit which extends longitudinally of the stove immediately beneath the series of burners 6, and is provided with a series of openings 14 which 100 are arranged concentrically with openings in the lower ends of the burners 6. The bottom of the stove casing directly beneath and at one side of the burners 6 is provided with a series of openings which permit a 105 circulation of air from the floor to the burners. The construction of the fire back, and especially when used in connection with a stove as above outlined, enables the gas flame to be broken up and retarded, which 110 causes it to take a secondary mixture with the air and spread among the several pro-

jections throughout the entire height of the flame. This produces perfect combustion and an intense flame, resulting in an economical heat as well as a combustion that is free from carbon and the conditions which form poison carbon monoxid gas; the perfect combustion derived from the construction of the fire back results in a cleaner, sanitary stove. Other advantages are such 10 as result in the fire back being quickly heated with a minimum of flame and when used in conjunction with a stove such as disclosed, enables the heat to be deflected downwardly in such intense rays that the 15 cold air in the room is quickly displaced and rapidly circulated from the floor over the reflecting plates and the fire back. It has been found in practice that a fire back embodying the features of the present invention is a distinct improvement over the asbestos or copper fire backs, as it is more rapid in heating, cleaner in combustion and appearance.

I claim:—

- 25 1. A fire clay back for heaters embodying in its structure, a plurality of staggeredly arranged projections extending outwardly at right angles from the face thereof, some of said projections comprising solid heat absorbing units, and other of said projections comprising hollow heat absorbing units, said solid units being located on the lower surface of the fire clay back and said hollow units being located above said solid units.
- 30 2. A fire clay back for heaters comprising a plate adapted for application to a gas heater and overhang the burners thereof,

said plate embodying in its structure, a plurality of staggeredly arranged projections 40 extending outwardly at right angles from the face thereof, some of said projections comprising solid triangular shaped heat absorbing units and other of said projections comprising V shaped hollow heat absorbing 45 units; said solid triangular shaped units being located on the lower surface of said plate, and having the apex of one of their angles disposed downwardly, and said hollow V shaped units being located above said 50 solid units and also having the apex of one of their angles disposed downwardly.

3. In combination with a gas heating stove having a casing and a plurality of burners, of an inwardly inclined fire back 55 overhanging said burners, said fire back comprising a plate composed of fire clay and embodying in its structure a plurality of staggeredly arranged projections extending outwardly at right angles from the 60 face of the plate in position to intercept the flame produced by said burners; some of said projections comprising solid triangular heat absorbing units and other of said projections comprising hollow V 65 shaped heat absorbing units, said triangular shaped units disposed with the apex of one of their angles pointing toward the burners, and said V shaped units disposed with the apex of one of their angles toward 70 said solid units.

The foregoing specification signed at Ironton, Ohio, this 24th day of January, 1916.

JACOB E. DAVIS.
